Specification for Design.

Patented Jan. 3, 1922.

Application filed January 22, 1921. Serial No. 439,297. Term of patent 14 years.

To all whom it may concern:

Be it known that I, GUSTIE M. CLEMETSON, a citizen of the United States, residing at Park River, in the county of Walsh and State of North Dakota, have invented a new, original, and ornamental Design for a Shade and Curtain Fixture, of which the following is a specification, reference being had thereto in the accompanying drawings.

I claim:

The ornamental design for a shade and curtain fixture, as shown.

In testimony whereof I hereunto affix my signature.

GUSTIE M. CLEMETSON.
